DISPLAY RACK FOR TOOL BOXES OR THE LIKE

Lawton L. Shurleff, Lafayette, Calif., assignor to Thorsen Manufacturing Company, a corporation of California

Application October 23, 1957, Serial No. 48,214

Term of patent 14 years

(Cl. D80—10)

The figure is a front perspective view of a display rack for tool boxes or the like, showing my new design.

I claim:

The ornamental design for a display rack for tool boxes or the like, as shown.
